Primary Examiner—A. Hugo Word*Assistant Examiner*—Doris V. Coles[57] **CLAIM**

The ornamental design for a fishing dressing holder, as shown and described.

DESCRIPTION

FIG. 1 is a front elevational view of a fishing dressing holder, showing my new design;

FIG. 2 is a front elevational view in the unfolded position;

FIG. 3 is a rear elevational view in the folded position;

FIG. 4 is a rear elevational view in the unfolded position;

FIG. 5 is a side elevational view in the unfolded position, the opposite side being a mirror image thereof;

FIG. 6 is a side elevational view in the folded position, the opposite side being a mirror image thereof;

FIG. 7 is a bottom plan view thereof; and,

FIG. 8 is a top plan view thereof.
